UNITED STATES PATENT OFFICE.

WILLIAM V. ROBINSON, OF DETROIT, MICHIGAN, ASSIGNOR TO THE ART STOVE COMPANY, OF SAME PLACE.

DESIGN FOR A STOVE.

SPECIFICATION forming part of Design No. 34,088, dated February 12, 1901.

Application filed January 21, 1901. Serial No. 44,232. Term of patent 7 years.

To all whom it may concern:

Be it known that I, WILLIAM V. ROBINSON, a subject of the Queen of Great Britain, residing at Detroit, in the county of Wayne and State of Michigan, have invented and produced a certain new and original Design for Stoves, of which the following is a specification, reference being had therein to the accompanying drawing, in which the design is shown in perspective.

A is a rectangular body having plain unbroken vertical walls, excepting as hereinafter described. B is a top plate extending beyond said body to form an overhanging flange. C. Upon the front face of said body are arranged the rectangular doors D, E, and F, the latter two being arranged in vertical line with each other and at one side of the door D. The door D is formed with a marginal raised band or border F, having ornamental

corners G. Within said border is a plain panel H and a central raised ornament I. Beneath the door D is a raised ornament J.

One end wall of the body has the oblong rectangular raised damper-frame K extending horizontally across the end and near the top thereof.

The leading feature of the design is the rectangular body having the raised rectangular doors D, E, and F, arranged substantially as described.

What I claim as my invention is—

The design for a stove, substantially as herein shown and described.

In testimony whereof I affix my signature in presence of two witnesses.

WILLIAM V. ROBINSON.
